ORGAN CASE.

No. 16,498.

Patented Feb. 2, 1886.

*Fig. 1.**Fig. 2.*# UNITED STATES PATENT OFFICE.

LEVI K. FULLER, OF BRATTLEBOROUGH, VERMONT, ASSIGNOR TO THE
ESTEY ORGAN COMPANY, OF SAME PLACE.

DESIGN FOR AN ORGAN-CASE.

SPECIFICATION forming part of Design No. 16,498, dated February 2, 1886.

Application filed October 21, 1885. Serial No. 180,496. Term of patent 14 years.

To all whom it may concern:

Be it known that I, LEVI K. FULLER, a citizen of the United States, residing at Brattleborough, Windham county, Vermont, have 5 invented or produced a new and original Design for an Organ-Case, of which the following is a specification.

My design is clearly shown in the accompanying engravings, of which Figure 1 is a perspective view of the front of the case, and Fig. 2 is a perspective view of the rear thereof.

This design relates, principally, to the consoles and pillars for supporting the key-board projection. The end pieces of the key-board projection are extended laterally at their lower portions in the form of quarter-cylinders A A, arranged with their axes extending horizontally from front to rear. Beneath 10 these cylindrical extensions are the pillars B B of the consoles. The end pieces of the key-board projection have vertical front faces and angularly-inclined tops, as shown. The lower portions of their front faces are extended 15 laterally at a a toward the outside beyond the front ends of the quarter-cylinders A A. These lateral extensions a a have an irregular or scalloped outline on their outer sides, and the front face of each is embellished with a figure 20 in lines, as shown.

Beneath the extension a and quarter-cylinder A is a projecting molding or cornice, b, and beneath this is the cube-like capital c of the pillar B, between which and the pillar 25 30 35

35 is a projecting plate or molding, d, having cut-off corners and concave sides. The pillars B B are of novel design. The top of each is shaped with annular ribs or corrugations extending around it. Beneath 40 this it has the semblance of an inverted cup, e, with serrated edge. A little lower down it has a band, f, extending around it, the surface of which is roughened by being cut diagonally to form diamond-shaped spaces. At 45 the bottom of the pillar, where it rests on the square base, it is inclined out to form a foot, g, which is divided by vertical lines into segments.

The back of the case is flat, and is divided into four vertical panels, C C, beneath, and 50 two horizontal panels, D D, above. In each of the latter are four vertically-arranged patterns or ornaments, as shown in Fig. 2.

I claim—

1. The design for an organ - case herein 55 shown and described, the same consisting of the lateral extensions A A at the base of the ends of the key-board projection, each being in the shape of a quarter-cylinder.

2. The design for an organ - case herein 60 shown and described, consisting of the end pieces of the key - board projection, with the quarter-cylindrical extensions A A projecting laterally from their lower portions, and pillars beneath these extensions.

3. The design for an organ - case herein 65 shown and described, consisting of the end pieces of the key-board projection, with angularly-receding tops and vertical front faces, the vertical faces extended laterally at a a, 70 and the quarter-cylindrical lateral extensions A A at the base of the end pieces, behind the lateral extensions a a of said front faces.

4. The design for an organ - case herein 75 shown and described, the same consisting of the end pieces of the key-board projection, with the quarter-cylinders A A, the cornices b b, the cube-like capitals c c, and the pillars B B.

5. In a design for an organ-case, the design 80 for the consoles herein shown and described, the same consisting of the pillars B B, each having the inverted cup-like ornaments e, the roughened band f, and the foot g.

6. In a design for an organ-case, the design 85 for the back thereof herein shown and described, the same consisting of the lower panels, C C, the upper panels, D D, and the ornamental figures in the upper panels, as shown.

In witness whereof I have hereunto signed 90 my name in the presence of two subscribing witnesses.

LEVI K. FULLER.
